UNITED STATES PATENT OFFICE.

CHRISTIAN J. SIEBENHAAR, OF ORAMEL, NEW YORK.

WALL-PAPERING MACHINE.

1,071,812.

Specification of Letters Patent. Patented Sept. 2, 1913.

Application filed September 20, 1912. Serial No. 721,426.

To all whom it may concern:

Be it known that I, CHRISTIAN J. SIEBENHAAR, a citizen of the Kingdom of the Netherlands, residing at Oramel, in the county of Allegany and State of New York, have invented new and useful Improvements in Wall-Papering Machines, of which the following is a specification.

The present invention relates to certain 10 novel and useful improvements in wall papering machines.

In carrying out my invention, it is my purpose to provide a machine of the character described whereby the edge of the 15 paper may be trimmed, and the paper applied to and pasted on the wall or ceiling, rapidly and accurately.

A further object of my invention is the provision of a machine embodying in its 20 construction, the desired features of simplicity, durability and convenience, the machine being so constructed that the operator in using the same stands at a distance from the wall being papered, thereby enabling 25 him to determine whether or not the patterns or rolls are matching and also to determine the accuracy of the work.

Still another object of my invention is to provide a novel arrangement of support for 30 the pasting brushes, said support being actuated by the operator to raise and lower the same as hereinafter described.

I also aim in the present instance to provide a machine which may be manufactured 35 and marketed at a relatively low cost.

With the above-recited objects and others of a similar nature in view, the invention consists in the construction, combination and arrangement of parts set forth and falling 40 within the scope of the appended claims.

In the accompanying drawing:—Figure 1 is a view in side elevation of the machine embodying my improvements, the machine being shown in its extended position. Fig. 45 2 is a vertical longitudinal sectional view, taken through the same. Fig. 3 is a transverse vertical sectional view. Fig. 4 is a top plan view. Fig. 5 is a perspective view of the paper roll holder and the pasting rolls 50 and receptacle.

Referring now to the accompanying drawings in detail, the letter A indicates the platform of my machine, said platform being provided with casters 1 for moving the 55 same from place-to-place. Arranged at one end of the platform are the standards 2—2,

carrying the cross bar 3 having the bore 4 therein for the reception of the screw 5, the outer end of said screw carrying a crank or handle 6. The shank of the screw is 60 threaded into the cross bar 7 of the vertically arranged movable frame 8, said frame having rollers 9 by means of which the frame may travel along the platform a certain distance, when the screw is actuated. To the vertical standards 10 of the frame is pivoted one end 11 of the lazy tongs 12, the opposite end of said lazy tongs being pivoted as at 13 to the end of the platform from that carrying the screw. 70 The lazy tongs, it will be seen, form an extensible body or frame for carrying parts of the wall paper machine, as will be hereinafter described. When the screw shank is turned to the left by means of the handle 75 or crank, the extensible frame formed by the lazy tongs is extended or lengthened, the movable frame 8 traveling toward the center of the platform. When the movement of the screw is reversed or it is turned 80 toward the right, the frame is lowered, the frame being retracted toward the end of the platform.

Mounted upon the platform and beneath the lazy tongs frame are the paper holding 85 devices and the paste receptacle and paste applying devices which may now be described as follows:—The numerals 14—14 indicate side members in which is removably journaled a paper holding roll 15, one 90 end of the shaft of the roll fitting in an open slot 16 while the opposite end of the shaft of the roll is journaled in the opposite side support. By this means the roll may be removed when desired. The side supports are vertically slotted as at 17, for the reception of the end studs of the roller 18, whereby said roll may be elevated and lowered into contact with the inclined 19 to which is attached the cutting knife 20. 100 The roll is grooved as at 21 for the reception of the cutter knife or plate by means of which the edge of the paper is trimmed. The roll should be sufficiently heavy to hold the paper on the slanting cutter board while 105 the latter should be sharpened enough to easily cut the edge of the paper while the machine is being opened. By placing the roll in the slots as described, the operator may lift the roll and let the paper pass 110 under the same. The side supports carrying the paper holding roll and the cutter roll

are formed with the projecting lugs or ears 22 in which is journaled the paper guide roll 23. This guide roll rests directly over the paste applying mechanism which is as follows:

The numeral 24 indicates the paste receptacle which is in the form of a box or the like, while 25 and 26 indicate upper and lower paste applying rolls, respectively, the lower paste roll being rotatably journaled in the side members 27, while the upper roll 25 is journaled in the vertical slots 28 of said members, the springs 29 bearing against the studs of said upper roll and holding the latter in yielding engagement with the lower pasting roll. The paper which is indicated at P, as it comes off of the guide roll 23 passes beneath the pasting roll and thence beneath a guide roll 30 journaled in the projecting ends of the members carrying the feed roll. The sides of the paste box are provided with angular slots 31 and 32, respectively, for the reception of pins 33 and 34, carried by each of said members, the construction and arrangement being such that these members which are connected by the cross bar 35 may be moved slightly relative to the paste box, the members and the cross bar forming a frame for the pasting rolls and the guide roll at the end thereof. The paper, after passing the guide roll 30 leads upward and over the paste brush 36 carried at the top of the lazy tongs frame, the end of said paper being then held by the paper clamp which comprises a flat strip 37 secured to the top of the frame, said strip being supported upon the blocks 39 which are formed with vertically extending ears 40 for the reception of the rod 41. To this rod is pivoted through means of the ears 43, a movable strip 44, said clamping strip being normally held in closed position relative to the stationary strip by means of the coiled spring 45. The movable strip is also provided with pins 46 designed to penetrate the paper and extend through alining apertures 47 in the stationary strip. Carried by the top of the lazy tongs frame are the two longitudinal bars 48, extending in parallelism and each formed with a longitudinally extending slot 49, terminating in a curved enlargement 50.

The numerals 51—51 indicate two bars each having a hooked head portion 52 each of said heads having connected thereto a laterally extending stud 53 projecting through the adjacent slot 49 of the slotted side bars each of the studs carrying a retaining block 54. The bars 48 are also provided with other slots 55, elongated in the direction of the length of the bar, said slots receiving the cross rod 56 connecting the end of the top links of the lazy tongs, and the ends of said bars are further connected by a cross rod 57.

58 designates a brush roller carried at the enlarged ends 59 of the bars 51, said brush being designed to apply the ceiling paper as hereinafter described. Immediately in front of the brush is a means for holding the edge of the paper roll comprising a stationary cross strip 60 extending between the bars, and a movable strip 61 pivoted to the rod 62 and normally held in engagement with the stationary strip by means of a coil spring 63, this device for retaining the end of the paper roll being similar to that at the opposite end of the frame, as heretofore described.

In order to remove the pivoted strips of the paper end holders and thereby release the same, I provide wires or cords 64—64' connected to the pivoted or movable strips of the clamps, said wire or cord extending downward to the platform, within easy reach of the operator so that it is only necessary to pull the cord to open the clamp and thereby release the paper.

It will be seen that the bars 51, carrying the ceiling brush and paper clamp are slideable in the slots 49 of the bars 48, so that they may be drawn outward or extended as desired, the studs 53 at the large ends of the bars 51 resting within the curved portions 50 of the slots 49. Thus, the curved ends of the slots form abutments for limiting the movement of the brush carrying bars.

From the above description, taken in connection with the accompanying drawings, the construction and manner of employing my improved wall paper machine will be readily apparent to those skilled in the art.

By turning the screw to the left through means of the handle or crank, the lazy tongs will be extended and the machine raised in which position it is ready to paste the paper on the wall. As the tongs are extended, the paper is drawn off the paper roll, past the edge trimming knife, and through the paste-applying rolls, where the paste is applied to the proper face of the paper. The machine is now moved forward on the casters until the wall pasting brush rests against the wall, when the operator releases the paper from the holding clamp by pulling on the wire or cord after which the machine is closed by reversing the direction of the screw. As the machine collapses or closes, the table will be drawn downward along the wall and the paper appropriately pasted. In applying the paper to the ceiling, the top bars carrying the ceiling brush and paper clamp are extended relative to the slotted bars, so that they over-reach the length of the machine. The paper is placed in position when the machine is closed, by attaching the edge of the paper in the clamp and as the machine is open or extended the necessary amount of paper will

be drawn off the roll. The machine is then run forward on its casters so that the paper will be applied to the ceiling by the ceiling brush, the edge of the paper being properly released from the clamp by pulling the wire connection.

While I have herein shown and described one particular embodiment of my improved wall paper machine, by way of illustration, 10 I wish it to be understood that I do not confine the invention to all the precise details of construction herein set forth as modification and variation may be made without departing from the spirit of the invention or 15 exceeding the scope of the appended claims.

Having thus described my invention, I claim:—

1. In a wall papering machine, the combination with a platform, of an extensible 20 frame carried thereby, means for extending and collapsing said frame, a holder for the paper and paste-applying mechanism on said platform, and devices carried by said extensible frame for pasting the paper on a 25 wall or ceiling.

2. In a wall papering machine, the combination with a platform, of a frame, means for extending and collapsing said frame, a paper holder and paste-applying mechanism on said platform, and brushes carried by said extensible frame for pasting the 30 paper on the wall or ceiling.

3. In a wall paper machine, the combination with a platform, a frame movable 35 along the same, an extensible frame connected to the first-mentioned frame, means for moving the first-mentioned frame to extend and collapse the extensible frame, and paper pasting devices carried by the extensible 40 frame.

4. In a wall paper machine, the combination of a platform, a frame carried thereby, means carried by the top of the frame capable of being extended relative to the 45 frame, a paste brush carried by the extended means, and a device for clamping the paper arranged adjacent to the brush.

5. The combination with a platform, a frame carried thereby, a paper holding roll, 50 a paste receptacle adjacent to the paper holding roll, paste rolls at the paste receptacle, and a wall and a ceiling brush carried by said frame.

6. The combination of a platform, a 55 frame, a wall brush carried by the frame, a paper clamp adjacent to the brush, a ceiling

brush also carried by the frame, a paper clamp arranged adjacent to the ceiling brush, and means for opening the clamps to release the paper therefrom.

60

7. The combination with a movable platform, an extensible frame carried thereby, a paper holding roll, trimming mechanism adjacent to said roll, a paste receptacle, pasting devices on the receptacle, a wall brush carried by the top of the frame, and a ceiling brush at the opposite end of the frame from the wall brush.

8. The combination with a movable platform, of an extensible frame composed of 70 lazy tongs carried by said platform, and paper pasting devices carried by said lazy tongs frame.

9. The combination of a platform, of a frame comprising lazy tongs carried thereby, a paper roll holder on the platform, a paste receptacle adjacent to the rolls, a wall brush at the top of the frame, a clamp for the edge of the paper adjacent to said brush, a ceiling brush at the opposite end of the 80 frame from the wall brush, and a paper clamp adjacent to the ceiling brush.

10. The combination of a platform, a roll holding and paste applying mechanism thereon, a frame, a plurality of extensible 85 bars carried at the top of said frame, and wall and ceiling brushes carried by said bars.

11. The combination of a platform, an extensible frame carried thereby, means for 90 raising and lowering the frame, a roll for the paper roll, a paper edge trimmer adjacent to the roll, a paste receptacle, paste applying devices at the paste receptacle, a wall brush carried by the top of the extensible 95 frame, a paper clamp adjacent said brush and comprising a stationary strip and a pivoted spring tensioned strip, a ceiling brush at the opposite end of the frame from the wall brush, a paper clamp arranged adjacent thereto and comprising a stationary strip and a pivoted spring tensioned strip, and means for actuating the movable strips to release the paper during the pasting 100 process.

In testimony whereof I affix my signature in presence of two witnesses.

CHRISTIAN J. SIEBENHAAR.
